INVENTOR,
Ernest F. Rueckert,
BY ATTORNEY

UNITED STATES PATENT OFFICE.

ERNEST F. RUECKERT, OF PROVIDENCE, RHODE ISLAND.

VANITY BOX.

Application filed September 6, 1924. Serial No. 736,334

To all whom it may concern:

Be it known that I, ERNEST F. RUECKERT, a citizen of the United States, residing at Providence, in the county of Providence and 5 State of Rhode Island, have invented new and useful Improvements in Vanity Boxes, of which the following is a specification.

This invention relates to vanity boxes, and has for an object the provision of an 10 article of this character in which loose powder, coins, a puff, a rouge compact or similar articles may be conveniently carried by a person either in a hand bag or suspended from the body.

15 The invention further consists of the novel features of construction, combinations of elements and arrangements of parts herein-after to be fully described and claimed.

A full and complete understanding of the 20 invention may be obtained from a consideration of the following detailed description, taken in connection with the accompanying drawing forming a part of this specification, it being understood that while the drawing

25 shows a practical form of the invention, the latter is not to be confined to strict conformity with the showing thereof, but may be changed or modified, so long as such changes and modifications mark no material departure from the salient features of the invention, as specifically pointed out and claimed.

In the accompanying drawing, wherein 30 similar reference characters designate corresponding parts throughout the several figures:—

Figure 1 is a perspective view of the vanity box constructed according to this invention;

40 Figure 2 is a similar view of a portion thereof illustrating the powder puff in position for use;

Figure 3 is a longitudinal central sectional view of the device;

45 Figure 4 is a sectional view taken on the line 4—4 of Figure 3 and looking in the direction of the arrows;

Figure 5 is a similar view taken on the line 5—5 of Figure 3;

50 Figure 6 is an end elevation showing the filling opening and closure therefor;

Figure 7 is a perspective view illustrating the construction of the powder puff; and

Figure 8 is a fragmentary sectional view

showing the manner in which a larger container may be accommodated within the box.

Referring to the specific embodiment of the invention illustrated in the accompanying drawing, the vanity box 1 comprises a substantially cylindrical receptacle portion 2 having its edge at one end, flared outwardly to provide the peripheral flange 3, over which the outer portion of the bottom 4 is clinched as at 5 to hold the bottom firmly thereon. A second bottom or shutter 6, similar in shape to the bottom 4, is positioned over the latter, with its entire inner surface in engagement with the outer surface of said bottom, and it carries centrally 70 of its outer surface, the U-shaped member 7 which serves both as a handle for turning the shutter with respect to the bottom 4, to bring the apertures 8 and 9 into alignment and thus permit filling of the receptacle 2 with powder, and also as a means for suspending the vanity box upon a ribbon or chain from the neck of its owner.

The open end of the powder receptacle or container 2 is partially closed by the apertured metallic disk or washer 10, which is held in position by the inturned flange 11. The powder puff 12 comprises three superimposed disks 13, 14 and 15 of chamois skin or like soft material, and is held in position 85 in the receptacle 2 by a second metallic washer 16, which is disposed between disks 14 and 15, and is centrally slotted to provide a plurality of triangular shaped tongues 17, which pass through aperture 18 in disk 15 and are bent up in engagement with the underside of washer 10. The disk 14 is disposed between the larger disks 13 and 15, which are sewed or otherwise secured together at their outer edges, and has its periphery stitched to the disk 13 to provide a powder pocket into which the powder 19 enters through central aperture 18, and from which it is permitted to pass as needed through a series of perforations 21 in the disk 13 to the outer surface thereof. The puff is carried by the powder receptacle with its central perforated portion communicating with the interior of said receptacle and receiving powder therefrom, and the edges 90 of said puff either in a contracted position (Fig. 3) or spread out over the inner end of the receptacle, as shown in Fig. 2. When

95

100

105

the edges of the puff are folded and contracted, the puff projects beyond the inner end of the powder receptacle 2, and its diameter when contracted does not exceed the 5 diameter of the receptacle. To enclose the projecting portion of the puff there is provided a telescoping sleeve 28, which, when slid to its innermost position, or toward the flange 3, exposes the puff, but when moved 10 to its outermost position or away from the said flange, the sleeve forms a continuation of the powder receptacle and encircles the folded and contracted portion of the puff. When in the last-mentioned position, the 15 cap 22 forms a complete closure for the puff.

The interior and exterior diameters of the lower portion of the cap are equal to the like dimensions of the receptacle 2, and the upper portion flares outwardly as at 24, and 20 is inturned to provide the flange 25, which secures the mirror 26, constituting the top of the cap, in position.

The ring 27 aids in maintaining the mirror in position and limits the movement of 25 the cap 22 into the sleeve 28, the cap fitting between the outer end of the sleeve and the contracted portion of the puff and retained in this position by a sliding fit.

The sleeve 28 has an outwardly flared flange 30 29 which engages the ring 27 in the normal closed position of the box 1, and the sleeve is permanently associated with the receptacle 2 by the engagement of the integral struck up projection 30 within the groove 31 35 which limits and guides the movement of the sleeve relative to the receptacle (Fig. 4).

A small metallic container 32 is carried in the cap 22, and may be used as a container for rouge, coins or any other small articles. 40 In Figure 8 of the drawing is illustrated the construction employed when a comparatively large container 33 is carried within the cap. It will be observed from a comparative study of Figures 3 and 8 that the additional space necessary for receiving the larger container is secured by lengthening the portion of the annular ring 27, which engages the inner side of the sleeve 28. As the engagement 45 of the sleeve 28 with the ring 27 determines the extent to which the cap 22 is telescoped by the sleeve, it is evident that the greater the length of the ring 27 the greater will be the space within the cap between the puff 12 and the mirror top 26.

50 In the practice of the invention, when it is desired to use the puff 12, the box 1 is tapped, while in an inverted position with the mirrored cap down, to cause a sufficient amount of the powder 19 to fall into the pocket of the puff. The sleeve 28 is then moved over the receptacle portion 2, toward the flange 3 thereby exposing the projected contracted portion of the puff the cap 22 removed and the puff flattened out ready for use. The cap may be held in one hand with

its mirror in position for use while the puff is being applied with the other.

When it is desired to return the puff to its enclosed position, the sleeve is moved outwardly toward the open end of the powder 70 receptacle, and by its engagement contracts the puff as it moves thereover. The cap is then inserted over the puff and within the sleeve to completely close the box.

From the foregoing description it will be 75 evident that this invention provides a receptacle for powder, and a puff in a neat and attractive form which entirely encloses them within a casing of small dimensions when not in use. This provides a unique and attractive article which will appeal to the public.

What is claimed is:—

1. A device of the class described comprising a powder receptacle, a puff carried 85 by said receptacle and normally contracted and projecting from the inner open end thereof and communicating therewith, a sleeve telescoping over said receptacle, said sleeve when in one position exposing the puff 90 and in the other position enclosing the same, and a cap closing the outer end of the sleeve.

2. A device of the class described comprising a powder receptacle, a puff carried 95 by said receptacle and normally contracted and projecting from the inner open end thereof and communicating therewith, a sleeve telescoping over said receptacle, said sleeve when in one position exposing the puff, so that it may be spread out over the 100 end of said receptacle in position for use and in the other position enclosing the sides of the puff; and a cap telescoping within the sleeve and closing over the puff in its contracted folded position.

3. A device of the class described, comprising a powder receptacle, a puff carried by said receptacle, said puff having a pocket communicating with said receptacle and receiving powder therefrom and having perforations, a sleeve telescoping over said receptacle and in one position contracting the puff and maintaining it contracted and in another position exposing the puff so that it may be spread over the end of the receptacle, 110 and a cap for the receptacle.

4. A device of the class described comprising a powder container, a puff operatively mounted at one end of the container and projecting therefrom and carried thereby, said puff when in position for use being spread out over the said end of the receptacle, means permitting passage of powder from the container to the puff, a sleeve slidably mounted on the outside of the container for contracting the puff by sliding around the spread-out puff, and a removable cap 120 fitting within said sleeve and over said puff.

5. A device of the class described comprising a powder container, a puff operatively 130

mounted at one end of the container, a sleeve slidably mounted on the container for contracting the puff, and a cap removably fitting within the sleeve and over the puff, said cap having a mirror on its outer face.

6. A device of the class described comprising a powder container, a puff operatively mounted at one end of the container, a sleeve telescopically engaging the container 10 for contracting the puff, a removable cap fitting within the sleeve and over the puff, said cap forming an auxiliary receptacle.

7. A device of the class described comprising a powder container, a puff operatively 15 mounted at one end of the container, means permitting passage of powder from the container to the puff, a sleeve slidably mounted on the container for contracting the puff, and a removable cap fitting within 20 the sleeve and over the puff, the top of the cap comprising a mirror for use in conjunction with said puff and the interior of the cap forming an auxiliary receptacle.

8. In a device of the class described, a 25 puff comprising a pair of disks having their peripheries secured together, a smaller disk disposed therebetween and having its edge secured to one of said disks to provide a pocket, an aperture in said small disk, and perforations in the disk to which said small disk is secured.

9. In a device of the class described, a 30 puff comprising three disks secured together, one between the other two, the middle disk being smaller than the others and having a central opening, one of the two outer disks

being provided with a central opening and the other outer disk having perforations.

10. A device of the class described comprising a powder receptacle, a puff carried by said receptacle and normally projecting from the inner open end thereof and communicating therewith, a sleeve telescoping over said receptacle, said sleeve when in one position exposing the puff and in the 40 other position enclosing the same, and a cap for the outer end of the sleeve.

11. In a device of the class described, a powder container, a puff carried thereby and adapted to be contracted to a diameter not 45 greater than the diameter of the container, and projecting from the inner end of the container, and when in use adapted to be spread out over the end of the container, a sleeve telescoping over the container, said sleeve in one position contracting the puff and maintaining it in its contracted condition and in another position exposing the 50 puff for use, and a cap for closing the sleeve and covering the puff when not in use. 60

12. In a device of the class described, a powder container having a fixed and a movable bottom, apertures in said bottoms, means for rotating said movable bottom to align said apertures, said means constituting 65 a support for the container, a puff in the container, and means for dispensing power into and through the puff.

In testimony that I claim the foregoing 70 as my own, I have hereto affixed my signature.

ERNEST F. RUECKERT.
